UNITED STATES PATENT OFFICE.

WILLIAM J. VERTREES, OF BUSHNELL, ILLINOIS.

TROUGH.

1,076,724.

Specification of Letters Patent.

Patented Oct. 28, 1913.

Application filed December 12, 1911. Serial No. 665,303.

To all whom it may concern:

Be it known that I, WILLIAM J. VERTREES, a citizen of the United States, residing at Bushnell, in the county of McDonough and State of Illinois, have invented certain new and useful Improvements in Troughs, of which the following is a specification.

This invention relates to improvements in the feed trough disclosed in Patent No. 906396, dated December 8, 1908, and its object is to provide a trough of greater strength and rigidity, and also one which is lighter, and which can be more cheaply manufactured.

With these objects in view, the invention consists in a novel construction and arrangement of parts to be hereinafter described and classed.

20 In the accompanying drawing, forming a part of this specification, Figure 1 is a perspective of a trough constructed in accordance with the present invention. Fig. 2 is a longitudinal section, and Fig. 3 is a

25 cross-section on the line 3—3 of Fig. 2. Referring specifically to the drawing, 5 denotes the body portion of the trough, the same being formed of a plate of suitable sheet metal which is bent into semi-cylindrical form, and has outwardly extending longitudinal flanges 6 at its top. The end walls of the trough are rectangular sheet metal plates 7 having their inner sides formed with a semi-cylindrical groove or depression 8 in which the ends of the body portion 5 seat. At the bottom of the end walls 7 are outstanding horizontal flanges 9 forming supporting feet for the trough. At the top of the end walls are inturned horizontal flanges 10, which overlap the end portions of the flanges 6, and are riveted or otherwise secured thereto as indicated at 11. At the vertical edges of the end walls the material is folded back upon itself as indicated at 12 to stiffen said walls.

Tongues 13 are punched up from the end walls 7 close to the groove 8. These tongues are so located that they lie outside the body portion 5 of the trough, and they are bent out from the end walls and passed through 50 slits 14 in the body portion 5, adjacent to the ends thereof, and clenched or folded back against the inner surface of the latter. By this method the end walls are securely fastened to the body portion of the 55 trough, and in order to obtain a water-tight joint between the parts, the contacting portions of the trough body and the end walls are soldered, and the exposed ends of the tongues are also embedded in solder. 60

By arranging and assembling the parts as herein described, a trough is had which can be cheaply manufactured, and a strong and rigid structure is produced which will stand rough usage. The flanges 6 may also be connected by a transverse brace 15 which is located midway between the ends of the trough.

I claim:

A trough comprising a body portion having slits adjacent to its ends, end walls having grooves in their inner faces in which grooves the ends of the body portion seat, and tongues punched out of the end walls outside of the grooves, said tongues projecting from the inner side of the end walls and extending along the outer surface of the body portion at the ends thereof, the free ends of the tongues passing through the slits of said body portion and being 75 clenched on the inside thereof.

In testimony whereof I affix my signature in presence of two witnesses.

WILLIAM J. VERTREES.
